UNITED STATES PATENT OFFICE

GIUSEPPE FOSSATI, OF MONZA, ITALY, ASSIGNOR TO FABBRICA ITALIANA MAGNETI MARELLI SOCIETÀ ANONIMA, OF MILAN, ITALY, A COMPANY OF ITALY

IGNITION MAGNETO

Application filed July 30, 1930, Serial No. 471,818, and in Italy September 5, 1929.

The present invention relates to ignition magnetos for internal combustion engines.

One of the objects of this invention is a body or frame for ignition magnetos which provides a unitary structure or casing adapted to enclose all the parts of the magneto, said casing being open on one face and having recesses adapted to contain the several magneto parts and which lead to said open face, while a removable cover is located on said open face of said casing and is passed through by the magneto parts which are required to extend outside of said casing for the magneto drive and control and for distribution of the current generated by said magneto.

Another object of the invention is a device for fastening said cover on said magneto casing.

A further object of the invention is an arrangement for the location and mounting of the removable magneto parts in said casing, as a condenser or the like.

On the annexed drawings are shown by way of example an embodiment of the present invention and

Figure 1 is a front view of the magneto body of the invention as seen from the current distributor end and deprived of its cover;

Figure 2 is a side view of the same;

Figure 3 is a view from the opposite end with respect to Fig. 1;

Figure 4 is a fragmentary transverse section of the magneto body on line 4—4 of Figures 2 and 5;

Figure 5 is a fragmentary plan section on the line 5—5 of Fig. 4, with a condenser located in a space of said casing.

Figure 6 is a fragmentary front end view on an enlarged scale of the magneto body with a cover and cover fastener;

Figure 7 is a fragmentary plan section on the line 7—7 of Figure 6.

As shown in the drawings, the magneto body consists of a unitary casing which comprises an intermediate portion 1 providing a bottom plate 2 for mounting the magneto on a supporting member of an engine,

and an end seat 3 for bearings of the magneto shaft.

At its front end said body 1 provides an integral hood 4 adapted to contain at its top a current distributor, not shown, and at its bottom a circuit breaker and ignition advance means.

Hood 4 is closed by a cover 5 fastened thereon by fastening means hereinafter described and located in the body recesses 19; means for drive and control of the magneto and leads feeding current to sparking plugs (not shown) extend through said seat 3 and cover 5.

The body 1 provides a chamber 7 for the magneto armature, a bore 8 in which a magneto rotor is mounted to rotate, and a number of recesses made therein for the purpose of reducing its weight, some of said recesses being capable of use for the location of magneto parts, as a condenser as hereinafter described.

The bore of the seat 3 is adapted to receive a bearing for the magneto driving shaft, and a suitable gland or packing device is provided therein.

The body according to the invention may be conveniently produced by casting and it may enclose within it the parts of the iron or magnetic circuit as pole shoes and the like; it provides a unitary structure and thus any joint and connecting means may be omitted. This feature is of great importance, it having been found that screws and other connecting means are subject to loosening under the vibrations that the magneto undergoes during operation, and finally, the openings of the casing in register with the hood 4 and bearing seat 3 may be fluid sealed by a suitable mounting of the cover 5 and driving shaft.

As above referred to, recesses provided in the magneto body 1 may be availed of to arrange therein parts required for the magneto operation; such an arrangement is shown in Figures 4 and 5 in respect to the condenser usually found in the primary circuit of the magneto and connected across the poles of the primary circuit breaker.

As shown in Figures 4 and 5, a bore 9 made

in said magneto body 1 comprises a seat providing a shoulder 10 and extending into a tapering recess 11. A condenser 12 which consists, as known, of a pair of conducting sheets coiled with an intermediate insulating sheet in the shape of a cylinder, is located in said seat 9 and is clamped therein by a split ring 13 seated in a groove 14 provided near the mouth of the seat 9.

10 The outer layer of the condenser 12 is thus in direct contact with the mass of the magneto body 1, while its internal layer is connected with a central terminal 15 lying in register with the mouth of the bore 9.

15 Thus the condenser 12 may be easily located in the magneto body and removed therefrom, and one of the body recesses is availed of for its location without a space for a condenser having to be purposely provided; 20 further, the condenser is held safely in position without fastening the screws which are liable to become loose.

25 Of course condensers of any shape and construction may be used for the purposes of the present invention and the shape of the bore or space 9 availed of for the condenser location may be any preferred one instead of cylindrical as illustrated by way of example.

30 Figures 6 and 7 show a preferred construction of means for mounting the cover on the magneto body.

35 As shown in said figures, an enlargement 16 is provided on each side of the magneto body 1 and a bore 17 having a seat 18 shaped as a portion of a sphere is provided in said enlargement, said bore opening on a side in a transverse slot 19 open to the outside.

40 A ball head 20 of a stem 21 is engaged in said seat 18 and said stem 21 has a flange 22 at its end opposite said ball head. Stem 21 is encircled by a sleeve 23 having an in-turned end flange 24 and a head 25 on its opposite end, said head 25 having transverse lugs 26; a spring 27 is located intermediate 45 stem 21 and sleeve 23 and the respective flanges 22 and 24.

45 The connecting member consisting of the stem 21 and sleeve 23 may be easily mounted by inserting the spring 27 into sleeve 23 and then the stem 21 into said spring 27 and sleeve 23 with its ball end 20 forward, said stem being inserted through a bore of the sleeve head 25 which thereafter may be closed in any suitable manner, say by a plug 28.

50 Of course, the described arrangement is duplicated on each side of the magneto.

55 Said connecting member is then engaged with the magneto body 1 by inserting the head 20 into bore 17 and causing the restricted portion 21' of stem 21 connecting it with the end ball 20 to pass through the slot 19.

60 Said resilient connecting member is thus engaged with the body 1 and then it is elongated and moved into a recess 29 of the cover 5, the head 25 and lugs 26 of the same being

then engaged in a seat 30 of said cover to hold it in position.

To remove said resilient connecting member and cover, a pull is exerted on the head 25 to elongate said member and remove its head 25-26 from the cover seat 29-30; thereafter the said connecting member is moved through 90° with respect to the position of Figure 7; it is then held in such position by the abutment of the outer end of the sleeve flange 24 against the side of the body enlargement 16 due to the action of the spring 27.

65 After the cover 5 has been located again on the magneto body 1, said connecting member is moved back into the position of Figure 7, it entering again said cover seat 29 while the lugs 26 of head 25 again engage the front recesses 30 of the cover 1.

70 Of course many modifications lying within the spirit of the appended claims may be embodied in the construction which has been described merely by way of example.

75 What I claim as my invention and desire to secure by United States Letters Patent is:—

1. A body for ignition magnetos comprising a casing open on a face, said casing providing an intermediate portion intended to contain the magneto field system, an end seat for a shaft bearing and a front hood receiving the current distributor and breaking mechanism of the magneto, a front cover closing said hood and passed through by magneto control means, and the current feeding means, and an extensible resilient member interconnecting said casing and cover, said member consisting of two telescoping parts and a spring intermediate the same, one of said parts being floatingly anchored in a seat of one of said casing and cover members and the other part engaging cooperating means on the other of them.

80 2. A body for ignition magnetos comprising a casing open on a face, said casing providing an intermediate portion intended to contain the magneto field system, an end seat for a shaft bearing and a front hood receiving the current distributor and the breaking mechanism of the magneto, a front cover closing said hood and passed through by the magneto control means, and the current feeding means, and an extensible resilient member interconnecting said casing and cover, said member comprising a part having an end ball head floatingly anchored in a seat of one of said casing and cover members and a flange on its opposite end, a sleeve having an in-turned end flange passed through by said ball head and enclosing said flange of said first named part, a spring intermediate said sleeve and first named part and abutting on said respective flanges, and means on said sleeve engaging the other one of said casing and cover members.

85 3. A body for ignition magnetos compris.

- ing a casing open on a face, said casing providing an intermediate portion intended to contain the magneto field system, an end seat for a shaft bearing and a front hood receiving the current distributor and the breaking mechanism of the magneto, a front cover closing said hood and passed through by magneto control means, and the current feeding means, and an extensible resilient member interconnecting said casing and cover, said member comprising a part having an end ball head floatingly anchored in a seat of one of said casing and cover members and a flange on its opposite end, said seat having a transversely open slot leading thereinto, a sleeve having an inturned end flange passed through by said ball head and enclosing said flange of said first named part, a spring intermediate said sleeve and first named part and abutting on said respective flanges, and means on said sleeve engaging the other one of said casing and cover members.
4. A body for ignition magnetoes comprising a casing open on a face, said casing providing an intermediate portion intended to contain the magneto field system, an end seat for a shaft bearing and a front hood receiving the current distributor and the breaking mechanism of the magneto, a front cover closing said hood and passed through by magneto control means, and the current feeding means, and an extensible resilient member interconnecting said casing and cover, said member comprising a part having an end ball head floatingly anchored in a seat of one of said casing and cover members and a flange on its opposite end, said seat having a transversely open slot leading thereinto and opening in an outer surface transverse to that in which opens said spherical seat a sleeve having an inturned end flange passed through by said ball head and enclosing said flange of said first named part, a spring intermediate said sleeve and first named part and abutting on said respective flanges, and means on said sleeve engaging the other one of said casing and cover members.
5. A body for ignition magnetoes, comprising an integral hollow casting in the form of a casing having a front wall at one end and being open at the other end, said front wall providing a seat for a shaft bearing, a front hood on said open end adapted to receive the current distributor and breaking mechanism of the magneto, said casing being provided, in a lateral wall, with a hollow space open at one end, a condenser located in said hollow space with one of its armatures in direct contact with said casing, resilient means engaging said condenser in said space, a cover adapted to close said hood of said casing, and resilient means for removably connecting said cover with said casing.
6. A body for ignition magnetoes, comprising an integral hollow casting in the form of a casing having a front wall at one end and being open at the other end, said front wall providing a seat for a shaft bearing, a front hood on said open end adapted to receive the current distributor and breaking mechanism of the magneto, said casing being provided, in a lateral wall, with a hollow space open at one end, a condenser located in said hollow space with one of its armatures in direct contact with said casing, resilient means engaging said condenser in said space, a cover adapted to close said hood of said casing, and resilient means for removably connecting said cover with said casing.
7. A body for ignition magnetoes, comprising an integral hollow casting in the form of a casing having a front wall at one end and being open at the other end, said front wall providing a seat for a shaft bearing, a front hood on said open end adapted to receive the current distributor and breaking mechanism of the magneto, said casing being provided, in a lateral wall, with a cylindrical hollow space open at one end, a rolled condenser located in said hollow space with its outer surface in direct contact with said casing, resilient means engaging said condenser in said space, a cover adapted to close said hood of said casing, and resilient means for removably connecting said cover with said casing.
8. A body for ignition magnetoes, comprising an integral hollow casting in the form of a casing having a front wall at one end and being open at the other end, said front wall providing a seat for a shaft bearing, a front hood on said open end adapted to receive the current distributor and breaking mechanism of the magneto, said casing being provided, in a lateral wall, with a cylindrical hollow space open at one end, the surface confining said hollow space being provided with an annular recess at its outer end, a rolled condenser located in said hollow space with its outer surface in direct contact with said casing, an expandible ring removably seated in said annular recess and engaging said condenser in said space, a cover adapted to close said hood of said casing, and resilient means for removably connecting said cover with said casing.
- In testimony whereof I have signed my name to this specification.
- GIUSEPPE FOSSATI.
